POLISH ROD

Jeddy D. Nixon, Houston, Tex., assignor, by mesne assignments, of fifty percent to Wilson Supply Company

Application December 12, 1936, Serial No. 115,494

6 Claims. (Cl. 255—28)

This invention relates to new and useful improvements in polish rods.

One object of the invention is to provide an improved polish rod device for use in wells and the like, particularly adapted to sheath a worn or marred polish rod.

An important object of the invention is to provide means so arranged as to sheath or enclose the surface of a polish rod which has become worn or scarred, whereby the working surface of the rod may be renewed or replaced in a simple, economical and expeditious manner.

Another object of the invention is to provide a sheath or enclosure, adapted to be mounted on a polish or reciprocating rod, and made in tubular form and of such length that less material is required in its construction, than is necessary for a solid polish rod, whereby a considerable saving in material and cost is had.

20 A further object of the invention is to provide means for fastening the sheath or sleeve on a polish rod, whereby the sleeve may be readily secured to the rod at various elevations and adjusted longitudinally of said rod, as conditions 25 may require.

A construction designed to carry out the invention will be hereinafter described, together with other features of the invention.

The invention will be more readily understood 30 from a reading of the following specification and by reference to the accompanying drawing, in which an example of the invention is shown, and wherein:

Figure 1 is a view of a device constructed in 35 accordance with the invention and mounted in a well head, partly in section and partly in elevation;

Figure 2 is an enlarged view of the device, partly in section and partly in elevation;

40 Figure 3 is a transverse, horizontal, sectional view taken on the line 3—3 of Figure 2;

Figure 4 is a similar view taken on the line 4—4 of Figure 2; and

45 Figure 5 is a transverse, horizontal, sectional view taken on the line 5—5 of Figure 2.

In the drawing, the numeral 10 designates a polish rod which may be mounted in a string of sucker or pumping rods 11 for a well, or used for 50 any other purpose for which it is adapted. An elongate sleeve or tube 12 is adapted to fit around or to enclose a portion of the polish rod. This sleeve may be formed of any suitable material, such as stainless steel, brass, or Monel metal, and the like. The upper end of the sleeve is swaged

or flared so as to form an outwardly extending rim or flange 13.

An annular housing or socket 14 has an axial bore 14' which receives the upper end of the sleeve 12, as will be seen in Figures 2 and 5. The upper portion of the socket is counter-bored at 16 and an inclined shoulder or seat 15 is provided between said bores. The flared flange 13 rests or seats upon the shoulder 15, so as to support said sleeve 11. Above the flange 13 and within the bore 16, is mounted a suitable sealing or packing ring 17, preferably of soft metal or rubber. An annular, upwardly flared, follower ring 18 is mounted above the packing ring 17, and within the upper end of the bore 16.

The upper end of the socket 14 is provided with external screw threads 19 for engaging with the internal screw threads 20 of the axial bore 22 of an annular head 21. At the upper end of said bore, an inclined seat 23 is formed, as will be seen 20 in Figure 2. For fastening the head 21 and socket 14 to the sucker or other rod 10, a plurality of arcuate gripping slips 24 are positioned within said head. Attention is called to Figure 2, in which it will be noticed that the upper and lower 25 ends of the backs of the slips are inclined to contact with the inclined seat 23 and the flared inner surface 18' of the ring 18. The inner face 30 of each slip is provided with serrations or teeth 25 for gripping the rod 10 extending through said slips. When the head 21 is rotated and the socket and sleeve held stationary, said socket will telescope the head, whereby the flared surface 18' and seat 23 will ride on the inclined ends of the slips, thus causing the latter to grip the rod 35 10. When the gripping action is complete and the rotation continued, the ring 18 being held from moving upwardly by the slips, will distort the packing ring 17, whereby the space between the upper end of the sleeve and the socket will 40 be sealed. The parts which have been described constitute a clamp, whereby the sleeve may be readily fastened on the polish rod 10 at the desired elevation or point intermediate the ends of said rod.

When the working surface of a polish rod becomes worn or marred, as by scores or pits, it will cut out packing and/or cause leaks. The practice has been to replace the rod, which is an expensive procedure. In using the invention, it is not necessary to replace the rod, but by simply removing one of the couplings and slipping the sleeve 11 and clamp onto the old rod, a new working surface is provided. It will be necessary, however, to provide a larger stuff- 45 50 55

ing box 36 to receive the sleeve. It is pointed out that as the old rod is retained, the sleeve may be considerably shorter in length than the rod.

5 As the sleeve need only be long enough to provide a working surface through the box 36, it will require greatly less material in structure than would be required for a new rod, therefore the cost will be considerably reduced and 10 a larger wearing surface will be had. It will be seen that by reason of the slips 24 and the screw threaded connection between the head 21 and socket 14, the clamp formed by these parts may be adjusted longitudinally of the polish 15 rod, thus enabling the proper positioning of the sleeve 11. The sleeve extends down through the usual casing or tubing head 30, upon which the T 34 is mounted to support the stuffing box 36. The tubing 32 may be supported on slips 33 in 20 the head or in any other suitable manner.

What I claim and desire to secure by Letters Patent is:

1. A polish device including, a guide sleeve, a 25 socket on the end of the guide sleeve, a head rotatably connected to said socket, gripping means within said head for securing said device onto a polish rod, and packing means within said socket arranged to be deformed by said 30 gripping means for forming a fluid-tight seal between said sleeve and polish rod.

2. A polish device including, a guide sleeve for receiving a polish rod, a socket on the end of the sleeve, means for connecting said socket and 25 sleeve together, a head rotatably connected to said socket, gripping means within said head for securing said device onto a polish rod, packing means within said socket for forming a fluid seal between said sleeve and a polish rod, and

means within said socket and head for actuating the gripping means.

3. A polish rod device including, an elongate tubular member adapted to receive a polish rod and having a smooth outer surface for working through a stuffing box, means for clamping said member on a polish rod intermediate the ends thereof, and yieldable means within the clamping means and distorted thereby to form a fluid seal at the end of the sleeve. 10

4. In a polish rod device, an elongate tubular member adapted to receive a polish rod and having a smooth outer surface for working through a stuffing box, a clamp including, a socket on the upper end of the tubular member and supporting the same, gripping means for engaging a polish rod, and a rotatable head having screw-threaded connection with the socket for longitudinally actuating the gripping means. 15

5. In a polish rod device, an elongate tubular member adapted to receive a polish rod and having a smooth outer surface for working through a stuffing box, a clamp including, a socket supporting the tubular member, gripping means for engaging a polish rod, a rotatable head having screw-threaded connection with the socket for actuating the gripping means, and packing means for forming a fluid seal in the socket when forced into position by the rotation of said head. 20

6. A polish device including, a guide sleeve, a socket on the end of the guide sleeve, a head rotatably connected to said socket, gripping means within said head for securing said device onto a polish rod, packing means within said socket, and operating means arranged to be actuated by the gripping means for deforming said packing means, whereby a fluid-tight seal is formed in said socket. 35
